[57] **CLAIM**

The ornamental design for a combined drawing tablet and cursor control for computer, as shown and described.

DESCRIPTION

FIG. 1 is a top plan view of combined drawing tablet and cursor control for computer and showing my new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a bottom plan view thereof;

FIG. 7 is a top plan view of the cursor control;

FIG. 8 is a left side elevational view thereof;

FIG. 9 is a right side elevational view thereof;

FIG. 10 is a rear elevational view thereof;

FIG. 11 is a front elevational view thereof;

FIG. 12 is a bottom plan view thereof; and

FIG. 13 is a top, front, right perspective view thereof.

The cursor control is omitted from FIGS. 2, 3, 4 and 5 and the drawing tablet is omitted from FIGS. 7-12 for convenience of illustration.
